CHAIR SEAT

Walter E. Nordmark, Grand Rapids, Mich., assignor to American Seating Company, Grand Rapids, Mich., a corporation of New Jersey

Application April 30, 1945, Serial No. 591,011

12 Claims. (Cl. 155—179)

1

The present invention relates to chair seats and more particularly to theater chair seats.

The primary objects of the invention are to provide an improved seat mounting frame for theater chair seats; to provide such a frame which may economically be made up from several sheet metal members; to provide such a seat frame having means whereby the seat springs and upholstery may readily be assembled to the frame to form a seat; to provide such a seat which may readily be assembled to or disassembled from a seat supporting pan turnably mounted on supporting standards; and to provide such a chair seat which is simple and sturdy in construction, economical in manufacture and attractive in appearance.

These objects are obtained by the illustrative embodiment of the invention shown in the accompanying drawings, wherein:

Figure 1 is a fragmentary perspective view of a theater type chair having a seat of the character above indicated;

Figure 2 is a fragmentary perspective view showing the chair seat in section taken on line 2—2 of Figure 1;

Figure 3 is a top plan view of the chair seat with a portion of the upholstery thereof broken away to disclose the seat frame below;

Figure 4 is an enlarged central vertical sectional view of the chair seat, taken on line 4—4 of Figure 1;

Figure 5 is an enlarged sectional view taken on line 5—5 of Figure 3;

Figure 6 is an enlarged sectional view taken on line 6—6 of Figure 3;

Figure 7 is an enlarged top plan view of the left front corner of the seat frame;

Figure 8 is an enlarged sectional view thereof taken on lines 8—8 of Figures 3 and 7;

Figure 9 is an enlarged sectional view of the seat frame per se taken on lines 9—9 of Figures 3 and 7;

Figure 10 is a fragmentary front perspective view of a seat front reinforcing wire, the foremost seat spring, and connections therebetween; and

Figure 11 is a fragmentary rear perspective view of a portion of the same.

Referring now in detail to these drawings wherein like parts are designated by the same numerals in the several views, the theater type chair therein illustrated comprises a pair of spaced vertical standards 1 only one of which is here shown, a conventional chair back generally designated 2 and consisting of a back plate

2

3 secured to the standards by means of screws 4, padding 5, and an upholstery cover 6. The chair seat is mounted on a seat supporting pan 7 of stamped sheet metal having conventional means indicated at 8 for turnably mounting the seat on the chair standards 1. The upper peripheral rim 9 of the pan 7 is curled inwardly and downwardly.

A seat frame 10 of generally rectangular configuration may be integrally formed of stamped sheet metal, but preferably and as here shown this seat frame consists of a front member 11, side members 12, 13 and a rear member 14, each of which members is provided with a longitudinally extending, downwardly stamped strengthening rib 15. As best seen in Figures 7 and 9, which show the front member 11 and side member 12 for the purpose of illustration, the adjacent pairs of these frame members have overlapping corner portions 16 on the front member 11 and 17 on the side member 12, the strengthening ribs 15 of which corner portions are nested together. One of these members, as here shown the side member 12, is provided with an inner flange 18 which is turned upwardly and outwardly over the corner portion 16 of the front member 11, and an outer flange 19 which is turned upwardly and inwardly, the flanges 18 and 19 thus gripping the corner portion 16 of the front member 11 therebetween and securing these two members in assembly. The other corners of the seat frame are similarly connected.

In the front member 11 and the rear member 14 of the seat frame 10, the strengthening ribs 15 are drawn downwardly and outwardly to form tongues 20, 21 in these members respectively, which tongues may be snapped between, and into engagement beneath the springable front and rear portions of the seat pan's rim 9, as best seen in Figures 5 and 6. The outer marginal edges of the front member 11 and the rear member 14 are turned upwardly and inwardly so that these members present smooth outer edges.

The side members 12, 13 of the seat frame 10, are each formed with an upstanding web 22 (see Figures 2 and 4) which is tapered from front to rear so that the forward portion of each is of greater height than the rearward portion, and with inwardly extending top and bottom flanges designated 23 and 24 respectively. The top flanges 23 of these side members 12, 13 have spaced extensions which are curled upwardly and outwardly to form hooks 25 for the attachment of upwardly arched sinuous springs 26 which

span the seat frame from side to side and which are here shown as five in number.

The inner marginal edges of the front member 11, the rear member 14, and the bottom flanges 24 of the side members 12 of the seat frame, are cut out to form inwardly extending spurs 27.

The seat upholstery comprises a sheet of upholstery material 28 of burlap or the like stretched over the springs 26 and around the seat frame 10 and attached to the spurs 27, padding 29 of hair or the like over and around the burlap, and an upholstery sheet or cover 30 of leather or the like stretched over the padding 29 and around the seat frame 10 and likewise attached to the spurs 27. The upholstery sheets 28 and 30 are pierced at their points of attachment to the spurs 27.

Means for reenforcing the forward portion of the seat in such manner that this portion is somewhat more resilient than the seat as a whole, comprises a resilient wire 31 having its opposite ends secured to hooks 32 on the side members 12, 13 of the seat frame, the hooks 32 being formed similarly to the hooks 25. The middle portion of the wire 31 is extended forwardly and upwardly beyond the foremost spring 26 and is attached to said spring by means of a connecting wire 33. This wire 33 has a U-shaped rear part 34 interlocking with the centermost undulations of the spring 26 and has laterally projecting parts 35 secured to the resilient wire 31 by means of clips 36.

It will be seen that the upholstered seat is slightly higher in the front than in the rear, this form being maintained by a combination of the resilient wire 31, the rearwardly tapering web 22 of the side frame members and the resultant decline in seat springs toward the rear, said springs being of equal length, and the increased gap between the rear spring 26 and the rearmost part of the seat.

The relatively wide bottom flanges 24 of the side frame members 12 which flanges are wider than the height of the webs 22, and the strengthening ribs 15, combine to lend rigidly to the seat frame and thus prevent any inward bowing at the sides thereof and eliminate the necessity for struts between the sides of the frame.

The invention provides a chair seat in which the upholstered seat and seat frame may be removed for repair or replacement without removing the seat supporting means from the standards, and the entire seat assembly is simple and sturdy in construction and reasonably economical in manufacture.

While but one specific embodiment of the invention has been herein shown and described, it will be understood that numerous details of construction may be altered or omitted without departing from the spirit of the invention as the same is defined by the following claims.

I claim:

1. In a seat structure, a seat supporting pan having an inwardly turned rim, a seat frame supported on the rim of the seat supporting pan, said frame having a portion thereof formed with a downwardly and outwardly extending tongue engaging beneath the inwardly turned rim of the seat pan, and means on the seat frame for the attachment of the seat.

2. In a seat structure, a seat supporting pan having an inwardly turned rim, a seat frame supported on the rim of the seat supporting pan, said frame having front and rear portions each formed with a downwardly and outwardly ex-

tending tongue engaging beneath the inwardly turned rim of the seat pan, and means on the seat frame for the attachment of the seat.

3. In a seat structure, a seat supporting pan having an inwardly turned springable rim, a seat frame supported on the rim of the seat supporting pan, said frame having front and rear portions each formed with a downwardly and outwardly extending tongue adapted to be forced between and to engage beneath the front and rear portions of the seat pan's springable rim, and means on the seat frame for the attachment of the seat.

4. In a seat structure, a seat frame having side portions provided with spaced hooks thereon and with inwardly extending spurs, a plurality of springs spanning the seat frame from side to side and having their opposite ends attached to said hooks, padding over the springs, and an upholstery cover stretched over the padding and attached to the spurs.

5. In a seat structure, a seat frame having side portions each comprising an upstanding web and inwardly extending top and bottom flanges, said top flanges having upwardly and outwardly turned portions forming hooks, and said bottom flanges having inwardly extending spurs, a plurality of springs spanning the seat frame from side to side and having their opposite ends attached to said hooks, padding over the springs, and an upholstery cover stretched over the padding and attached to the spurs.

6. In a seat structure, a seat frame having side portions each comprising an upstanding web and inwardly extending top and bottom flanges, one of said flanges being of greater width than the height of the web, said top flanges having upwardly and outwardly turned portions forming hooks, and said bottom flanges having inwardly extending spurs, a plurality of spring spanning the seat frame from side to side and having their opposite ends attached to said hooks, padding over the springs, and an upholstery cover stretched over the padding and attached to the spurs.

7. In a seat structure, a seat frame having side portions each comprising an upstanding web and inwardly extending top and bottom flanges, said web being of greater height in its forward portion than in its rearward portion, said top flanges having upwardly and outwardly turned portions forming hooks, and said bottom flanges having inwardly extending spurs, a plurality of springs spanning the seat frame from side to side and having their opposite ends attached to said hooks, padding over the springs, and an upholstery cover stretched over the padding and attached to the spurs.

8. In a seat structure, a seat frame having side portions each comprising an upstanding web and inwardly extending top and bottom flanges, said top flanges having upwardly and outwardly turned portions forming hooks, and said bottom flanges having longitudinally extending strengthening ribs and inwardly extending spurs, a plurality of springs spanning the seat frame from side to side and having their opposite ends attached to said hooks, padding over the springs, and an upholstery cover stretched over the padding and attached to the spurs.

9. In a seat structure, a seat frame having side portions provided with spaced hooks thereon and with inwardly extending spurs, a plurality of springs spanning the seat frame from side to side and having their opposite ends attached to said hooks, a sheet of upholstery material

stretched over the springs and attached to the spurs, padding over said sheet, and an upholstery cover stretched over the padding and attached to the spurs.

10. In a seat structure, a seat frame having side portions provided with spaced hooks thereon and with inwardly extending spurs, a plurality of upwardly arched sinuous springs spanning the seat frame from side to side and having their opposite ends attached to said hooks, a resilient wire having its opposite ends secured to the side portions of the seat frame and its middle portion extended forwardly and upwardly beyond the foremost spring, a sheet of upholstery material stretched over the springs and the resilient wire and attached to the spurs, padding over said sheet, and an upholstery cover stretched over the padding and attached to the spurs.

11. In a seat structure, a seat frame comprising front, rear and side members, each adjacent pair of said members having overlapping corner portions, and one of the members of each pair having at opposite sides of the corner portion thereof turned-over flanges embracing therebetween the corner portion of the other member of said pair.

12. In a seat structure, a seat frame having side

portions provided with spaced hooks thereon, a plurality of upwardly arched sinuous springs spanning the seat frame from side to side and having their opposite ends attached to said hooks, 5 a resilient wire having its opposite ends secured to the side portions of the seat frame and its middle portion extended forwardly and upwardly beyond the foremost spring, a sheet of upholstery material stretched over the springs and the resilient wire and attached to the seat frame, padding over said sheet, and an upholstery cover stretched over the padding and attached to the seat frame.
